FREE PISTON ENGINE

Hermann Jänicke, Dessau, Germany, assignor to
 Hugo Junkers, Munich, Germany; Therese
 Junkers, née Bennhold, administratrix of said
 Hugo Junkers, deceased

Application July 24, 1934, Serial No. 736,705
 In Germany July 31, 1933

19 Claims. (Cl. 123—46)

My invention relates to free piston engines, more particularly of the kind in which a pair of free pistons is arranged in a cylinder for reciprocation in opposite direction.

5 It is an object of my invention to improve engines of this kind in such manner that the overall length of the engine is considerably reduced.

In a free piston engine with a definite shape and arrangement of the parts the total length is 10 proportional to the stroke of the pistons and amounts to a definite multiple thereof. The stroke of the pistons is determined by the stroke volume required for the output of the engine in view of an efficient ratio of the length of the 15 stroke space to the inner diameter of the cylinder. In cylindrical combustion chambers an efficient ratio is obtained if the length of the stroke space is a multiple, for instance the three-fold to fourfold of the diameter. In consequence thereof in free piston engines and more particularly in engines having a large output and requiring a considerable stroke of the pistons, the total length is considerable. A long stroke of the pistons further involves the drawback that the period of oscillation is increased, thereby reducing the number of strokes per unit of time.

20 My invention allows considerably reducing the length of the stroke of the pistons and thereby also the overall length of the engine, and increasing the number of strokes per unit of time, while maintaining a suitable and efficient ratio of length to inner width thus establishing advantageous conditions of scavenging and of fuel distribution in the charge. By increasing the number of strokes all dimensions of the engine are 25 reduced at a predetermined output, thus further reducing the overall length of the engine.

In order to reduce the length of stroke of the pistons I provide an annular working space for 30 the pistons, the inner diameter being at least one third of the outer diameter. The inner wall of the working space may be formed by a stationary cylinder or by a cylindrical extension of one of the pistons, the extension being guided in a gas-tight manner in a hollow extension provided in 35 the other piston.

In the drawings affixed to this specification and forming part thereof some embodiments of my invention are illustrated diagrammatically by 40 way of example.

In the drawings

Fig. 1 is a diagram of one half on an annular working space and

Fig. 2 is a similar illustration of one half of 45 an ordinary cylindrical working space, both fig-

ures serving merely to explain the gist of my invention.

Fig. 3 is a sectional view of a free piston engine according to my invention.

Fig. 3a being a side elevation of a coupling 5 gearing forming part of the engine shown in Fig. 3.

Figs. 4—7 are sectional views of other embodiments,

Fig. 8 being a transverse section on the line 10 VIII—VIII of Fig. 7.

Figs. 9 and 10 are sectional views of other embodiments of the invention of a type similar to that shown in Fig. 4.

In all figures similar parts are marked with 15 the same reference numerals.

Referring to the drawings and first to Figs. 1 and 2, the working space or combustion chamber shown in Fig. 1 is annular in shape d and D being the inner and outer diameters, respectively, 20 while s is the length of the chamber. The inner width to the annular space is equal to

$$\frac{D-d}{2}$$

25

The cylindrical working space or combustion chamber shown in Fig. 2 has the length s_1 and the diameter D_1 . Be it assumed that the combustion chambers shown in Figs. 1 and 2 have equal volumes and equal ratios of length to inner 30 width or diameter amounting to 4:1. Hence

$$s=4 \cdot \frac{D-d}{2}$$

and $s_1=4D_1$.

Let us further assume that $D=2$, $d=1$, so that 35 $s=2$. Since the volumes of the combustion chambers are equal, it follows that

$$s(D^2-d^2)=s_1D_1^2$$

Thus

$$s_1D_1^2=4D_1^3=2(4-1)=6$$

40

Hence

$$D_1=\sqrt[3]{1.5}=1.145$$

$$s_1=4.58$$

Thus the ratio $s:s_1$ being equal to the ratio of the strokes amounts to 2:4.58.

This shows that by making the combustion chamber annular the length of stroke is reduced to more than one half of the length of stroke required in a cylindrical combustion chamber, the overall length of the engine being reduced correspondingly. By the reduction of the stroke the number of strokes per minute is increased, so that all dimensions of the engine may be reduced. 50 55

In making the combustion chamber annular, a space is rendered available in the cylinder forming the inner wall of the combustion chamber, which may advantageously be used in the operation of the engine, for instance as a chamber for scavenging air or exhaust gas, as a liquid tank, as the working chamber of a scavenging pump, as an energy storing device, as a compressor chamber or the like. If desired, however, auxiliary devices such as gearings coupling the free pistons with each other may be arranged in the inner cylinder, thus further reducing the space required by the engine. Embodiments of engines of this kind are shown in Figs. 3-7 which will be described more fully hereinafter.

The annular combustion chamber according to my invention further involves advantages in scavenging by providing scavenging and, if desired, exhaust ports in the inner as well as in the outer cylindrical wall of the combustion chamber. With the ports arranged in this manner the exhaust gases are more thoroughly removed, this effect being improved by the fact that the exhaust gases are allowed to extend farther into the working chamber. If scavenging ports only are provided in each wall, the exhaust ports being provided merely in one of the walls, the scavenging ports will be shorter than usual, while the exhaust ports have the usual length. Thus for the expansion of the exhaust gases a greater portion of the stroke, viz. the portion between the beginning of the opening of the exhaust ports and the beginning of the opening of the scavenging ports and in consequence thereof a longer period of time is available. If exhaust ports are also provided in each wall, the length of these exhaust ports is also reduced, so that no saving of time is obtained, but the total cross-section of the exhaust ports is increased, thus facilitating the expansion of the exhaust gases.

By shortening the exhaust ports the portion of the stroke volume not available for delivering energy, which corresponds to the length of the exhaust ports, is reduced with respect to the total stroke volume. Thus while maintaining the efficient stroke volume and the output of the engine, the total stroke of each piston is reduced by this reduction of the exhaust ports, the overall length of the engine being reduced by a multiple of this value, or, while maintaining the total stroke, the efficient stroke volume and thereby also the output of the engine may be increased.

The scavenging ports may be inclined to the radial direction, preferably in such manner that the currents of scavenging air entering the combustion chamber through the inner ports as well as through the outer ones carry out circulating movements of uniform direction, if possible at equal speed, so that they unite in a uniform circulating current of scavenging air.

In Fig. 3 1 is the outer cylinder forming the outer wall of the combustion chamber, 2 and 3 are compression cylinders having a larger diameter than cylinder 1 and forming extensions thereof. 4 and 5 are the end walls of the engine, to which the inner cylinder 6 extending over the total length of the engine is secured. The flying bodies are formed by the motor pistons 7, 8, the connecting members 9, 10 and the compressor pistons 11, 12, respectively. The outer cylinder 1 and the inner cylinder 6 enclose the annular working space or combustion chamber 13, the compressor chambers 14 and 15 being arranged at the ends of the engine and provided with suction valves 16 and pressure valves 17.

18, 19 are delivery pipes, through which the compressed gas or air produced in the engine is withdrawn. The spaces 20 and 21 existing between the combustion chamber 13 and the compression chambers 14 and 15, respectively, are designed as scavenging pump chambers and are provided with suction valves 22 and pressure valves 23. 24 is a pipe connecting the pressure valves 23 to the inner left hand space 25 of the inner cylinder 6 operating as a container for scavenging air 10 being connected to the combustion chamber by means of scavenging ports 27. The right hand portion 28 of the inner cylinder 6, which is separated from the left hand portion by a partition 26, is designed as an exhaust chamber connected to the combustion chamber 13 by exhaust ports 29 and leading the exhaust gases to the exhaust pipe 30. In order to obtain an accurately symmetrical reciprocation of the pistons, a gearing is provided comprising racks 31 and 32 connected to the compressor pistons 11 and 12, respectively, which engage a pinion 33 arranged for rotation about a stationary shaft. As will be seen from Fig. 3, two gearings of this kind are provided, one on each side of the engine, the other gearing being marked by the reference numerals 31', 32', 33'.

The operation of the engine is the same as that of the usual free piston engine and need not be described in detail. Fuel is delivered to the combustion chamber 13 by a suitable delivery nozzle or the like (not shown) and mixed with air. The charge is ignited, the pistons being driven apart. When the pistons approach their outer dead centre positions, the exhaust ports 29 and shortly thereafter the scavenging ports 27 are uncovered, so that the exhaust gases are withdrawn from the combustion chamber and scavenging air is supplied by the scavenging pump formed by the chambers 20 and 21. During the outward stroke of the pistons air is compressed in the combustion chambers 14 and 15, the compressed air being withdrawn through the pipes 18 and 19, except the air filling the dead volumes of the chambers 15 and 16, which will expand again and return the pistons into their inner dead centre positions, so that the cycle of operations can be repeated. It should be understood, that by designing the combustion chamber and the pistons in the manner above described the overall length of the engine is considerably reduced.

In the modified embodiment shown in Fig. 4 the diameters of the compressor pistons 11 and 12 and of the working pistons 7 and 8 are equal. In order to obtain a sufficient working surface of the compressor pistons, the length of the inner cylinder 6 is reduced so as to extend only substantially along the stroke of the motor pistons 7 and 8, respectively, supporting rods 34, 35 being provided within the range of the stroke of the compressor pistons 11 and 12, which extend through suitable perforations of the pistons 11 and 12, respectively. In order to obtain a sufficient amount of scavenging air, a partition 36 is provided in the right hand portion of the engine between the motor piston 8 and the compressor piston 12, which is packed with regard to the connecting member 10, two chambers 37 and 38, being thus formed, chamber 37 being connected to atmosphere by a port 39 formed in the outer cylinder, while the other chamber 38 forms the scavenging pump chamber together with the chamber 21 enclosed by the connecting member 10. 43 is a port formed in the wall of the connecting member 10 and connecting the chambers 21 and 38 with each other, the suction valve 22

and the pressure valve 23 of the scavenging pump being arranged in the manner indicated in Fig. 4. At the left hand portion of the engine the chamber 20 enclosed by the connecting member 9 is 5 not subdivided by a partition, but operates also as a scavenging pump chamber provided with pressure valve 23 arranged in the left hand end wall of the inner cylinder 6, the suction valve 22 being arranged in the wall of the outer cylinder 1. The working surface of this scavenging pump chamber is constituted by the difference of the cross-sections of the cylinder 6 and the supporting rod 34. If desired, the chamber 31 provided 10 at the right hand portion of the engine may be used as an operating chamber, for instance as an energy storing chamber, an additional compressor chamber, or a scavenging pump chamber. The chamber 31 may for instance be used as a second compressor stage. The gearing 31, 32, 33 coupling the flying bodies with each other is arranged in the inner space of the cylinder 6 except that portion of the racks 31, 32, which reaches to the points where the racks are fastened to the rear faces of the pistons 11, 12. The exhaust 15 ports 29 are provided in the wall of the outer cylinder 1, in which are also provided nozzles 40 for delivering fuel to the combustion chamber.

Fig. 5 illustrates an embodiment similar to that shown in Fig. 4. Here the inner cylinder 6 is not stationary but movable and connected to the motor piston 7. The other flying body comprising the motor piston 8, the connecting member 10 and the compressor piston 12, encloses an inner hollow space 21, in which the cylinder 6 is guided in a gas-tight manner. The chamber 21 is connected in the same manner as in Fig. 4 to an annular chamber 38, defined by the compressor piston 12 and the partition 36, the chambers 21 and 38 forming a scavenging pump delivering 20 scavenging air to a scavenging air tank 41 surrounding the outer cylinder 1 and being connected to the combustion chamber by scavenging ports 27. The chamber 37 defined by the motor piston 8 and the partition 36 is connected to the tank 41 by ports 42. The gearing coupling the flying bodies with each other is designed as a screw gearing, the greater part of which is arranged 25 within the inner cylinder 6. The gearing comprises a sleeve 44 having one end supported axially and undisplaceably in a cross member 45, being free to rotate around its axis. The outer ends of the cross member 45 are secured to the wall of the compressor cylinder 2. The connecting member 9 is provided with suitable longitudinal slots, through which the cross member 45 extends, so that it does not impede the free reciprocation of the pistons 7 and 11. The outer surface of the sleeve 44 is formed with a thread of high pitch engaged by a corresponding thread 30 formed on an extension 46 of the left hand flying body. The inner surface of sleeve 44 is formed with a thread of equal pitch and opposite direction to that of the outer surface, which is engaged by a threaded spindle 47 secured to the right hand compressor piston 12. Both flying bodies are secured against rotation, that on the left by the cross member 45, that on the right by a square rod 48 secured to the right hand end wall 5 of the engine and engaging a correspondingly shaped bore 49 formed in the spindle 47. Thus when the flying bodies reciprocate the sleeve 44 will carry out small reciprocatory angular movements without being axially displaced, and the threaded members connected to the flying bodies

and engaging the thread of the sleeve will secure an accurately symmetrical reciprocation of the flying bodies. If desired, the drive of auxiliary devices such as fuel, cooling water or lubricating oil pumps may be derived from the rotating sleeve 44. In the embodiment shown in Fig. 5 the end of the sleeve 44 is provided with a cam 51, driving the piston of a fuel pump 50 by means of a driving rod 52. The pump 50 delivers fuel to the inlet nozzles 40 through connecting pipes 53 and 54.

In order to cool the inner cylinder 6, an inset member 55 is provided which is secured to the cross member 45 by means of hollow rods 56. The inset member is hollow and arranged to withdraw heat from the cylinder 6. Cooling water is fed through a pipe 57 and through some of the hollow rods 56 and withdrawn through the other hollow rods 56 and a pipe 58.

The embodiment shown in Fig. 6 is similar to that shown in Fig. 5, however, the chamber 21 is designed not as a scavenging pump chamber, but as an energy storing chamber, to which energy is fed during the motor compression stroke, which is re-fed to the flying bodies during the motor working stroke. The wall 10 of the chamber 21 is provided near its outer end with ports 61, in which non-return valves 62 are provided, which open only into the chamber 21. The non-return valves define the amount of initial pressure in the chamber 21 existing before the beginning of the compression and they prevent the withdrawal of compressed air from the chamber 21.

The gearing for coupling the flying bodies with each other is designed in the embodiment shown in Fig. 6 as a hydraulic gearing, the coupling liquid of the gearing being used as a cooling liquid for the cylinder 6. To this end a casing 64 is arranged within the cylinder 6 which is secured to the left hand end wall 4 of the engine by means of a hollow rod 65. The casing 64 encloses two cylinders 66 and 67 in which pistons 68 and 69 respectively are arranged for reciprocation. Piston 68 is connected to the left hand flying body by means of a rod 71, piston 69 being connected in a similar manner to the right hand flying body by means of a rod 72, the rods 71 and 72 extending through the casing 64 at both end walls thereof in order to obtain equal working surfaces at each side of the pistons 68 and 69. The cylinders 66 and 67 are connected with each other at their ends and are filled with a suitable liquid, so that a displacement of one of the pistons in one direction causes a corresponding displacement of the other piston in opposite direction, thus securing a symmetrical reciprocation of the flying bodies. In order to use the coupling liquid filling the cylinders 66 and 67 as a cooling liquid for the inner cylinder 6, an intermediate chamber 73 packed at its ends is provided between the casing 64 and the cylinder 6, which is connected with the cylinder 67 by a port 74 and to the cylinder 66 by a non-return valve 75. At the left hand ends the cylinders 66 and 67 are connected with each other not directly, but by means of pipes 77 and 78 leading to a re-cooling device 76, the pipe 77 being connected to the cylinder 66 by a non-return valve 79. In consequence thereof during the outward stroke of the flying bodies the piston 68 forces the liquid at the left hand side through the non-return valve 75 into the annular chamber 73 and from there through port 74 into the cylinder 67. When flowing through the chamber 73 the liquid withdraws heat from the cylinder 6. Dur-

5 ing the subsequent return stroke the heated cooling liquid is forced from cylinder 67 through pipe 18 into the re-cooling device 76 and from there, after having been cooled, through pipe 11 back to cylinder 66, whereupon the cycle may be repeated, i. e. the cooling liquid passes from the cylinder 66 through the check valve 15 into the annular space 13 and from here through the opening 14 back into the cylinder space 67.

10 Thus it will be seen that a portion of the coupling liquid is continuously conveyed in a closed circuit through the cooling chamber 73 and the re-cooling device 76.

15 Figs. 7 and 8 illustrate an embodiment of my invention similar to that shown in Fig. 1. Here additional scavenging ports 27' are provided in the wall of the outer cylinder 1 which connect the combustion chamber with an annular chamber 25' connected to the scavenging pumps by connections 24 and 24'. Additional exhaust ports 29' are provided in the wall of the outer cylinder 1, opening into an annular chamber 28' connected to the exhaust pipe 30 by means of a pipe 30'.

25 As will be seen from Fig. 8, the scavenging ports 27 and 27' are inclined with respect to the radial direction in such manner that both the currents of scavenging air entering from the inner chamber 25 and from the outer chamber 25',
30 respectively, carry out in the combustion chamber circulations of uniform direction (indicated in Fig. 8 by the arrows *a* and *b*) which will unite into a single circulating current of scavenging air.

35 Fig. 9 illustrates an embodiment of the invention somewhat similar to that shown in Fig. 4, however distinguished therefrom by the fact that in Fig. 9 the partitions 36 and consequently also the spaces intermediate the partitions 36 and
40 the rear faces of the motor pistons 1 or 8 are arranged on both sides of the engine. On the right side of the engine the intermediate space 337 acts as a buffer space, in which during the motor working stroke energy is stored by the
45 compression of the gas contained in that space, the energy thus stored being again delivered during the return stroke. On the left hand side of the engine the intermediate space 137 acts as a working space of an additional scavenging
50 pump, the air being sucked in through the valves 122 and passing after compression through the valves 123, piping 124 and boring 125 provided in the structural member 34 into the interior of the cylinder 6, into which is passed also the scav-
55 enging air supplied from the spaces 21 through the valves 23. All other structural elements correspond to those illustrated and described with reference to Fig. 4 and are therefore provided with the same reference numerals as used in
60 connection with Fig. 4.

Fig. 10 likewise illustrates an embodiment of the invention of a type similar to that shown in Fig. 4, being similarly related to Fig. 9. However Fig. 10 illustrates a two stage compressor, in which the space 37 of Fig. 4 is modified, on both sides of the engine, as a compressor space 237 for the second compressor stage. The structural elements corresponding to those illustrated in Fig. 4 have likewise been marked with the reference numerals used in connection with Fig. 4. The embodiment according to Fig. 10 is distinguished from that shown in Fig. 4 quite particularly by the fact, that the pressure gas compressed in the compressor working spaces 15 is not at once supplied to the consumption place, but is passed

through the pressure valves 117, the pipes 118 and the suction valves 216 into the compressor spaces 231 of the second stage compressor. Here also the compressor space 231 is formed by the partitions 36 and the rear faces of the motor pistons 7 or 8. Only after compression in the compressor space 231 can the pressure gas be supplied, through the pressure valves 217 and the pipes 218, to the consumption place. 5

I wish it to be understood that I do not desire 10
to be limited to the exact details of construction
shown and described, for obvious modifications
will occur to a person skilled in the art.

I claim:—

1 claim.
1. A free piston motor compressor comprising 15
two cylinders, one arranged coaxially within the
other, a pair of annular free pistons arranged
for reciprocation in opposite directions in the
annular combustion chamber between said cylinders, 20
each piston being formed with a pair of faces
differing in size and being rigidly spaced
from each other more than the length of stroke
of each piston, and an energy consumer at either
end of the outer cylinder arranged to be acted 25
upon by the rear face of a piston and to consume
substantially all the energy generated in said
combustion chamber.

2. A free piston motor compressor comprising two cylinders, fixed to each other, one arranged coaxially within the other, a pair of annular free pistons arranged for reciprocation in opposite directions in the annular combustion chamber between said cylinders, each piston being formed with a pair of faces differing in size and being rigidly spaced from each other more than the length of stroke of each piston, the inner cylinder having a uniform diameter throughout the length of stroke of said pistons; and an energy consumer at either end of the outer cylinder arranged to be acted upon by the rear face of a piston and to consume substantially all the energy generated in said combustion chamber. 30 35 40

3. A free piston motor compressor comprising two cylinders fixed to each other, one arranged coaxially within the other, a pair of annular free pistons arranged for reciprocation in opposite directions in the annular combustion chamber between said cylinders, each piston being formed with a pair of faces differing in size and being rigidly spaced from each other more than the length of stroke of each piston, the inner cylinder extending substantially along the total stroke of said pistons; supporting means arranged in the axis of said inner cylinder and having a cross-section less than that of said inner cylinder, and an energy consumer at either end of the outer cylinder arranged to be acted upon by the rear face of a piston and to consume substantially all the energy generated in said combustion chamber.

4. A free piston motor compressor comprising two cylinders, one arranged coaxially within the other, a pair of annular free pistons arranged for reciprocation in opposite directions in the annular combustion chamber between said cylinders, each piston being formed with a pair of faces differing in size and being rigidly spaced from each other more than the length of stroke of each piston, the inner cylinder being connected to one of said pistons, the other piston comprising a hollow extension, means for guiding said inner cylinder in said extension in a gas-tight manner, and an energy consumer at either end of the outer cylinder arranged to be 75 65 70 75

acted upon by the rear face of a piston and to consume substantially all the energy generated in said combustion chamber.

5. A free piston motor compressor comprising two cylinders, one arranged coaxially within the other, a pair of annular free pistons arranged for reciprocation in opposite directions in the annular space formed by said cylinders, a gearing for coupling said pistons with each other, 10 said gearing being at least partly arranged within the inner cylinder, and an energy consumer at either end of the outer cylinder arranged to be acted upon by the rear face of a piston.

6. A free piston motor compressor comprising two cylinders, one arranged coaxially within the other, a pair of annular free pistons arranged for reciprocation in opposite directions in the annular combustion chamber between said cylinders, the inner cylinder being connected to one 15 of said pistons, a hollow extension formed in the other piston, means for guiding said inner cylinder in said extension in a gas-tight manner, and gas inlet and exhaust valves associated with said extension.

25 7. A free piston motor compressor comprising two cylinders, one arranged coaxially within the other, a pair of annular free pistons arranged for reciprocation in opposite directions in the annular combustion chamber between said cylinders, the inner cylinder being connected to one 30 of said pistons, a hollow extension formed in the other piston, means for guiding said inner cylinder in said extension in a gas-tight manner, and air inlet and exhaust valves associated with said extension for feeding scavenging air to the engine.

8. A free piston motor compressor comprising two cylinders, one arranged coaxially within the other, a pair of annular free pistons arranged for reciprocation in opposite directions in the annular combustion chamber between said cylinders, the inner cylinder being connected to one 40 of said pistons, a hollow extension formed in the other piston, means for guiding said inner cylinder in said extension in a gas-tight manner, and cooling means for the inner surface of said inner cylinder.

9. A free piston motor compressor comprising two cylinders, one arranged coaxially within the other, a pair of annular free pistons arranged for reciprocation in opposite directions in the annular combustion chamber between said cylinders, the inner cylinder being connected to one 50 of said pistons, a hollow extension formed on the other piston, means for guiding said inner cylinder in said extension in a gas-tight manner, a stationary member arranged in said inner cylinder, and common means for cooling said member and said inner cylinder.

60 10. A free piston motor compressor comprising two cylinders, one arranged coaxially within the other, a pair of annular free pistons arranged for reciprocation in opposite directions in the annular combustion chamber between said cylinders, the inner cylinder being connected to one 65 of said pistons, the other piston comprising a hollow extension, means for guiding said inner cylinder in said extension in a gas-tight manner, a stationary member arranged in said inner cylinder, an hydraulic coupling for said pistons and means for circulating liquid through said stationary member and said coupling.

11. A free piston motor compressor comprising two cylinders, one arranged coaxially within the other, a pair of annular free pistons arranged

for reciprocation in opposite directions in the annular combustion chamber between said cylinders, the inner cylinder being connected to one of said pistons, a hollow extension formed on the other piston, means for guiding said inner cylinder in said extension in a gas-tight manner, a stationary member arranged in said inner cylinder, means for cooling said inner cylinder through said member, an hydraulic coupling for coupling said pistons with each other, 10 means for circulating liquid through said stationary member and said coupling, and means for recooling the circulating liquid.

12. A free piston motor compressor comprising two cylinders, one arranged coaxially within the other, a pair of annular free pistons arranged for reciprocation in opposite directions in the annular combustion chamber between said cylinders, a gearing coupling said pistons and comprising an axially immovable member extending into 20 the inner cylinder and an axially fixed rod extending through one of said pistons and supporting said member.

13. A free piston motor compressor comprising two cylinders, one arranged coaxially within the other, a pair of annular free pistons arranged for reciprocation in opposite directions in the annular combustion chamber between said cylinders, a gearing coupling said pistons and comprising an axially immovable member extending 25 into the inner cylinder, and a fixed cross member extending radially through longitudinal slots in the side wall of one of said pistons, and supporting said axially immovable member.

14. A free piston motor compressor comprising two cylinders, one arranged coaxially within the other, a pair of annular free pistons held against rotation, but free to reciprocate in opposite directions in the annular combustion chamber between said cylinders, a screw gearing for coupling said 40 pistons extending into the inner cylinder, said gearing comprising an axially arranged sleeve threaded externally and internally in opposite directions and free to rotate but axially immovable, an internally and an externally threaded member, 45 said members being connected to said pistons and engaging the outer and inner threads of said sleeve, respectively.

15. A free piston motor compressor comprising two cylinders, one arranged coaxially within the other, a pair of annular free pistons arranged for reciprocation in opposite directions in the annular combustion chamber between said cylinders, each piston being formed with a pair of faces differing in size and being rigidly spaced 50 from each other more than the length of stroke of each piston and scavenging ports in the walls of each of said cylinders.

16. A free piston motor compressor comprising two cylinders, one arranged coaxially within the other, a pair of annular free pistons arranged for reciprocation in opposite directions in the annular combustion chamber between said cylinders, each piston being formed with a pair of faces differing in size and being rigidly spaced 65 from each other more than the length of stroke of each piston, and scavenging ports in the walls of each of said cylinders, all said ports being inclined in the same circumferential direction to the cylinder radii.

70 17. A free piston motor compressor comprising two coaxially arranged cylinders, one arranged coaxially within the other, a pair of annular free pistons arranged for reciprocation in opposite directions in the annular combustion chamber 75

- between said cylinders, each piston being formed with a pair of faces differing in size and being rigidly spaced from each other more than the length of stroke of each piston, the inner cylinder being connected to one of said pistons, a hollow extension formed on the other piston, means for guiding said inner cylinder in said extension in a gas-tight manner, and means enabling said extension to operate as an energy storage chamber.
- 10 18. A free piston motor compressor comprising two coaxially arranged cylinders, one arranged coaxially within the other, a pair of annular free pistons arranged for reciprocation in opposite directions in the annular combustion chamber between said cylinders, each piston being formed with a pair of faces differing in size and being rigidly spaced from each other more than the length of stroke of each piston, and scavenging and exhaust ports formed in the walls of each of
- 15 20 said cylinders.
19. A free piston motor compressor comprising in combination, a casing, a central motor work-

ing chamber in the middle part and a compressor working chamber at either end of said casing, two freely movable masses arranged in said casing for reciprocation in opposite directions, each movable mass being formed with an annular end face facing said motor working chamber and forming a piston face therein, and with another end face, differing in size from said annular end face and facing one of said compressor working chambers for operating as a piston face therein, a rigid connecting member between each pair of piston faces, said member being adapted to space said faces a distance which exceeds the stroke of that freely movable mass, to which the said connecting member appertains, an outer and an inner cylindrical wall, said walls confining between them said motor working chamber which is arranged between said annular piston end faces, a gearing connecting said freely movable masses for synchronous motion in opposite directions.
